UNITED STATES PATENT OFFICE.

CHARLES E. POPE, OF PITTSBURG, PENNSYLVANIA.

COKE-QUENCHING AND COKE-HANDLING APPARATUS.

984,700.

Specification of Letters Patent. Patented Feb. 21, 1911.

Application filed December 22, 1909. Serial No. 534,451.

To all whom it may concern:

Be it known that I, CHARLES E. POPE, a citizen of the United States, and a resident of Pittsburg, Pennsylvania, have invented 5 certain new and useful Improvements in Coke-Quenching and Coke-Handling Apparatus, of which the following is a specification accompanied by drawings.

This invention in its most complete form 10 comprises apparatus for quenching coke by spray in a closed chamber and it avoids drenching and over saturation of the coke and at the same time obtains the bright, silvery appearance of bee-hive coke, and saves 15 much labor and handling.

The invention in its preferred form is embodied in the apparatus described and claimed in this specification and shown in the accompanying drawing, which is a longitudinal elevation partly in section.

Referring to the drawings, A represents a coke oven shown conventionally, and B is a pusher.

C represents a dock and D is a barge to 25 which the quenched coke is to be delivered, although the coke could be delivered to cars, instead of a barge.

E represents a crane of any suitable form provided with the traveling carriage F.

30 The coke is handled and quenched in a carrier or receptacle G which may also be termed a "cradle", preferably of open-work construction and built of angle irons. This cradle may carry a full charge of ten tons 35 of hot coke. The cradle or receptacle G is suspended from the carriage F as by means of the rope or chain H and transported as desired.

J represents the quenching tank, which 40 may be built of concrete or brick laid in Portland cement, with interior dimensions, sufficient to receive the cradle holding the hot coke. As shown, the tank J is built partly above ground and partly under 45 ground, but it could be built entirely under ground to suit other conditions around the plant.

The cradle may be of suitable shape, as for instance, square or rectangular, and the 50 tank may be built to correspond.

Means are provided within the tank J for 55 quenching the coke and in this instance spray pipes K and L are shown, one part way down the height of the tank and the other arranged above. There is preferably a false bottom O in the tank to hold the

cradle. Water is supplied to the spray pipes K and L from the pressure tank P or other suitable source. The water is introduced part way down the tank as shown, to thoroughly spray the bottom of the coke and the steam arising will quench the upper half of the coke in the cradle. A drain pipe Q carries off the water preventing its accumulating to a depth sufficient to reach the coke, as 60 plainly shown.

Means are provided for substantially enclosing the cradle full of coke within the tank as by means of the cover plate R connected to the spacing frame S for the connecting chains T. The chains U connect the spacing frame and cover plate with the cradle and as the cover plate is lowered the chains U follow down into the tank and the cover fits over the top of the tank and 70 retains the steam necessary for quenching the coke, so that the bright silvery appearance of bee-hive coke is obtained.

The cradle may be provided with a drop bottom of any suitable form illustrated in 80 the form of doors V to deposit the coke from the cradle and suitable means may be provided for holding and releasing the doors V.

The guide pieces W placed at the door of the oven A are used when the cradle G is 85 standing in front of the oven and the oven is being discharged, for by this means loss of coke is prevented.

In the operation of the apparatus a charge 90 of coke is received by the cradle G and is then transported by the crane and the cradle and its charge placed in the tank J with the cover closed down. After the quenching is effected the cradle and its charge are raised and transported and the coke dumped into 95 the barge D or placed upon a car. Other cars or vehicles Y may be provided on which the cradle may be removably mounted and transported.

According to this invention the bright silvery appearance of the coke is obtained, like 100 that of bee-hive coke quenched while in the oven in the hot state. This result alone is a great improvement over the practice in connection with by-product coke, as by-product coke is black when it is quenched in the open air.

If desired, the cradle itself and its contents could be dropped into the barge, towed 110 to its destination, and the cradle hoisted and delivered into the furnace bin without any handling whatever. By this means large

pieces of coke could be insured and practically all of the breeze now wasted would be avoided at places where coke is handled in the usual manner.

5 I claim and desire to obtain by Letters Patent the following:

1. In coke quenching apparatus, the combination of an open-work coke carrier or receptacle adapted to receive hot coke, a quenching tank adapted to receive said receptacle, a cover for substantially inclosing the receptacle within the tank during quenching and substantially excluding air, and means for transporting said coke receptacle to and from said tank.

15 2. In coke quenching apparatus, the combination of an open-work coke carrier or receptacle adapted to receive hot coke, a quenching tank adapted to receive said re-

ceptacle, means for transporting said coke 20 receptacle to and from said tank, said receptacle being provided with a cover for closing the said tank when receiving the receptacle.

3. In quenching apparatus, a quenching 25 chamber, a movable carrier or receptacle provided with a cover for closing the chamber when receiving the receptacle, and means for jointly actuating the receptacle and the cover.

30 In testimony whereof I have signed this specification in the presence of two subscribing witnesses.

CHARLES E. POPE.
